UNITED STATES PATENT OFFICE

ARTHUR C. POTTER, OF NORTH WOODSTOCK, CONNECTICUT

DESIGN FOR A MATCH BOOK

Application filed October 13, 1930. Serial No. 37,250. Term of patent 14 years.

To all whom it may concern:

Be it known that I, ARTHUR C. POTTER, a citizen of the United States, residing at North Woodstock, in the county of Windham and State of Connecticut, have invented a new, original, and ornamental Design for Match Book, of which the following is a specification, reference being had to the accompanying drawings, forming part thereof.

Fig. 1 is a front view of a match book, and Fig. 2 is an edge view, showing my new design.

The rear of the match book is blank or contains printed matter.

I claim:

The ornamental design for the match book as shown and described.

ARTHUR C. POTTER.
